GARTER

Edgar O. Loeber, Cleveland, Ohio, assignor to
 William W. Taylor, East Cleveland, Ohio, as
 Trustee

Application December 4, 1934, Serial No. 755,920

1 Claim. (Cl. 241—6)

This invention relates to a garter or hose supporter. In devices of this character, of which I have knowledge, provision has been made to support the hose by means of bands (usually elastic or spring metal bands) arranged to entirely or partially encircle the leg above the calf and bound thereto by the spring or resilient characteristic of the band material, and to utilize the binding or clamping effect of such bands to not only secure them in position on the leg independently of the hose but by means of vertically depending elements to enable the bands to support the hose. Devices of this type are objectionable since certain blood arteries extend down the leg to supply blood to the numerous capillaries therein and from the capillaries the blood returns through the veins. While normally the pressure of the blood in the arteries is relatively high, its pressure in the veins is relatively small, so that any binding effect is detrimental in stopping the blood circulation in the rear portion of the leg where the artery and veins are located more or less near the surface and is readily sensed by the wearer by a sensation in the entire leg or in the gastrocnemius muscle. In more serious cases, this binding effect has caused varicose veins; in other cases where hardening of the artery tissue has set in, this binding effect has tended to retard the functioning of the artery, thereby accelerating the existing physical condition. In other cases this binding effect has affected the gastrocnemius muscle of the leg to the discomfort of the wearer.

One object of the invention is to construct an improved garter wherein provision is made to engage that portion of the wearer's leg which is not or will not be affected thereby and to eliminate all binding on other parts or portions of the leg.

Another object of the invention is to provide an improved garter having a leg engaging member and hose connecting devices so arranged that the leg engaging member and hose co-act through the connecting devices to hold the member in position and to support the hose.

A further object of the invention is to provide an improved garter of simple construction permitting ready application to and removal from the leg of the wearer.

Other objects of the invention will be apparent to those skilled in the art to which my invention relates from the following description taken in connection with the accompanying drawing, wherein

Fig. 1 is a side view of a human's leg showing

in position a garter embodying my invention and supporting a hose.

Fig. 1a is a section on the line 1a—1a of Fig. 1.

Fig. 2 is substantially a rear view of the parts shown in Fig. 1. 5

Fig. 3 is a side view of the garter (enlarged), parts being broken away.

Fig. 4 is a plan view.

Fig. 5 is a section on the line 5—5 of Fig. 3.

Fig. 6 is a view of a modified form, parts being 10 broken away.

Fig. 7 is a section on the line 7—7 of Fig. 6.

Figs. 8, 9, 10 and 11 show different embodiments of the invention.

Fig. 12 is a section on the line 12—12 of Fig. 11. 15

In the drawing, A indicates a human's leg and B indicates a hose thereon. 1 indicates as an entirely a garter comprising (a) a resilient member 2 having a front portion 2a shaped to substantially fit the front part of the leg and side 20 portions 2b arranged to extend loosely around the sides of the leg, to a point slightly rearwardly of an imaginary line a (Fig. 1) cutting the largest calf portion of the leg and (b) a pair of connectors 3 connected to the member 2 and extending rearwardly in an inclined direction for detachable engagement with the rearward portions of the hose, so that the pull or tension of the hose due to the weight of the hose or its tendency to resist stretching co-acts through the 30 side portions 2b of the member 2 with the portion 2a to press such latter portion against the adjacent or front portion of the leg. In this arrangement the pull through the connections 3 on the member 2 is in a rearward direction and 35 as the lower edges of side portions 2b bear against the sides of the leg above the larger calf portion thereof, and tend to prevent the rear ends of the member 2 from sliding downwardly, such pull on the portion 2a is substantially in a direction transversely of the leg, thereby lessening any tendency of the member 2 to slide downwardly on the leg A. Furthermore, as the connectors 3 are attached to the hose adjacent the rearward portion of the leg (see Fig. 2) and are connected 40 to the side portions 2b slightly rearwardly of the plane indicated by the line a, the connectors tend to flex the front portion 2a of the member 2 to the shape of the front portion of the leg, the effect of which is to further lessen the danger of 45 the member 2 to slide down the leg. It will thus be seen that since the leg engaging member 2 and connectors 3 are flat members having edge-wise resistance to deformation and have an angular relation, the latter being inclined rear- 50

55

wardly, the pull or tension effect required to support the hose is transmitted to that portion of the member 2 which engages the front part of the leg, to press it in a rearward direction into engagement with such part and by reason of such engagement the member is maintained in its proper position and the hose is supported thereby. In my form of construction, I provide two connectors which exert substantially equal tension or pull between spaced portions of the hose and the side portions of the member 2 so that pressure on the latter is substantially transversely of the leg and tendency to twist or rotate the member 2 on the leg is avoided. In the preferred arrangement, each connector 3 comprises an elastic section 3a having a main portion extending through a loop 4, its outer end carrying a suitable buckle 5 which frictionally engages the main portion to permit of adjustment of the effective length of the connector. The loop 4 carries a depending tab 6 to which is connected a pair of separable elements 7, 1a, of suitable construction adapted to permit attachment with the hose. By incorporating elastic sections 3a in the connectors 3, the pull effect or tension between the portion 2a of the member 2 and the hose B may be varied to insure adequate engagement of the member 2 with the front portion of the leg to hold it in position and also support the hose. This adjustment also permits a member 2 of a predetermined size to fit legs which vary largely in width or size circumferentially. The side portions 2b terminate at points slightly beyond the imaginary line a, so that their free ends are spaced widely apart and hence eliminate entirely danger of any pressure or binding effect on the rear portion of the leg, such ends preferably being flared outwardly to facilitate the positioning of the member 2 on the leg of the wearer.

The member 2 may be formed of suitable resilient material, including steel, rubber or celluloid and like material. The connectors 3 may be secured to the side portions 2b in any desired manner. Where the member 2 is formed of a material which does not require a cover, the connectors 3 may be secured to the side portions thereof by suitable metal parts including rivets. Where the member 2 is formed of rubber, celluloid or other molded material, each connector may be connected to a clip 3' which has portions embedded in the material as shown in Figs. 11 and 12. Where the resilient member is covered with a single layer of silk or fabric 8 (Figs. 3, 4 and 5) or a double layer (Fig. 6), each connector 3 extends in between the side portion 2b and the fabric and is sewed to the latter as shown at 8a. As shown in Fig. 8, the resilient member, indicated at 2z, may be relatively narrow, if desired, and enclosed in a pocket between layers of fabric 9, the fabric extending upwardly and downwardly beyond the member 2z and covered by silk 10 or other suitable material. The member 2z is held in the pocket by sewing the fabric as shown at 11. In this arrangement the connector 3 may extend through the cover 10 and in between the layers of fabric 9 and stitched thereto.

Fig. 9 shows a construction in which the re-

silient member comprises a plurality of relatively narrow flat elements 2' disposed between layers of fabric 12 which are sewed along intermediate lines 13 to form pockets for the members 2', the fabric 12 being preferably covered with silk 14 or other suitable material.

Fig. 10 shows a construction similar to Fig. 9 but in which the elements consist of wires 2x.

From the foregoing description it will be noted that the leg engaging member fits around the front part and sides of the leg to a point slightly rearwardly of the transverse imaginary line a and that the terminating ends 2c of the portions 2b bear lightly upon the sides of the leg only with sufficient pressure to off-set the tendency of the front portion 2a to gravitate due to its weight. In this connection it is to be noted that the member 2 is not formed of resilient material for the purpose of so clamping or binding the member 2 that it will support the hose but for the purpose of permitting the member to readily conform to legs of different sizes, to permit its ends to be spread in applying and removing the member and to simplify the construction whereby the terminating ends may yieldingly engage the sides of the legs for reasons above set forth. Such binding as may be incidental to the use of a resilient member has been found not to be detrimental. In the arrangement herein disclosed the necessary engagement of the member 2 with the leg to support the hose is at the front part of the leg entirely remote from those portions containing the arteries and veins. As the ends 2c are remote from the rear portion of the leg, this light pressure is, as I have determined, harmless. By compensating for the weight of the portion 2a, it will be noted that less pull or tension is required between the hose B and member 2 to hold the latter in engagement with the leg and this results in relieving discomfort to the wearer.

To those skilled in the art to which my invention relates, many changes in construction and widely differing embodiments and applications of the invention will suggest themselves without departing from the spirit and scope of the invention. My disclosures and the description herein are purely illustrative and not intended to be in any sense limiting.

What I claim is:

A garter or hose support comprising a resilient, curvilinear member formed of a relatively thin flat strip of metal shaped to provide a front portion arranged to engage the front portion of the wearer's leg and rearwardly extending side portions the ends of which yieldingly engage the sides of the leg and connectors adjustable endwise and consisting of flat elastic strips secured to said side portions inwardly of the ends thereof and extending therefrom at a rearwardly downwardly inclined angle and provided at their free ends with attaching devices for attachment with spaced portions of the hose rearwardly of the leg and serving to exert tension between said member and hose at an angle to the normal axis of the wearer's leg, whereby the resulting pressure or pull to support the hose is transmitted against the front portion of the wearer's leg.

EDGAR O. LOEBER.
